UNITED STATES PATENT OFFICE.

SAMUEL M. KINTNER, OF PITTSBURGH, PENNSYLVANIA, ASSIGNOR TO INTERNATIONAL DEVICES COMPANY, A CORPORATION OF DELAWARE.

SPEED GOVERNOR.

1,409,553.

Specification of Letters Patent. Patented Mar. 14, 1922.

Application filed November 19, 1919. Serial No. 339,043.

To all whom it may concern:

Be it known that I, SAMUEL M. KINTNER, a resident of Pittsburgh, in the county of Allegheny and State of Pennsylvania, have 5 invented a new and useful Improvement in Speed Governors, of which the following is a specification.

This invention relates to speed governors for controllable machines of various kinds, 10 such as steam engines, explosive motors, electric motors or other machines which are driven by an energy supply of any kind. The term "motor" is used herein to indicate any such machine.

15 The invention relates particularly to a type of speed governors such as illustrated and described in application of Alfred Vischer, Jr., Serial No. 216,057, filed February 8, 1918; having a double control, one control 20 being arranged to quickly change the supply of power producing element to the motor, and the other being arranged to slowly and cumulatively adjust said supply so as to accurately adjust the speed to the exact rate 25 desired.

This invention is an improvement upon the double control type of governors. Its object is to provide a construction better adapted than prior governors of the same 30 type for regulating motors in which the secondary or cumulatively adjustable feature is continued in operation over long periods of time.

In the accompanying drawings Fig. 1 is a 35 vertical sectional view of the improved governor; Fig. 2 is a plan view of the same, the top of the casing being removed, with parts in section on the line 2—2, Fig. 1; Fig. 3 is a horizontal section on the line 3—3, Fig. 1; 40 and Fig. 4 is a detail vertical section on the line 4—4, Fig. 2.

In the drawings 1 indicates a rotatable shaft adapted to be driven in any suitable way from the motor whose speed is to be controlled. This shaft may be mounted in any suitable bearings 2, and is shown provided with a worm wheel 3 driven from a worm gear 4 on a shaft 5 of the motor whose speed is to be controlled. 6 indicates generally the casing enclosing the governor, and 7 a rocking shaft connected to suitable means for regulating the supply of power producing element to the motor, such for instance as a throttle valve of a steam or internal combustion engine, a butterfly valve of an inter-

nal combustion engine, a regulator for an electric motor, or the like. Secured to the shaft 1 within the case 6 is a member 9 to which are pivotally secured two arms 10 of a suitable centrifugal governor, its arms being 60 provided at their free ends with weights 11. These arms are connected by links 12 to a member 13 slidable on the shaft 1 and which is forced to upward position by the helical spring 14 surrounding the shaft interposed 65 between the member 13 and a collar 15 threaded to the hub portion of member 9, by means of which the tension of said spring 14 may be varied as is obvious.

The member 13 is provided with a circumferential channel 16 in which engages a roller 17 rotatably mounted on one end of lever member 18 which is pivotally mounted on a stationary fulcrum 19 secured to the casing 6. This lever member 18 is of the 70 construction shown in Fig. 3, comprising a sleeve 18^a mounted on the fulcrum member 19 and with a short arm on which the roller 17 is mounted and its longer arm connected by link 20 to one arm of bell crank lever 21, whose other arm is connected by rod 22 to an arm or crank 23 on the rocking shaft 7. This lever connection from the member 13 to the shaft 7 provides means for quickly adjusting the power element control member, as 75 will be obvious. To provide for a variation of this control the arm of bell crank lever 21 to which the connecting rod 22 is attached is provided with a plurality of holes 24 located at different distances from the fulcrum of the lever 21, to either one of which holes the connecting rod may be attached.

The upper end of member 13 is provided with a cone face 25 which is engaged by one arm of each of a pair of bell crank levers 26 80 fulcrumed at 27 on a member 28 which is pinned or otherwise suitably secured to shaft 1, the other arms of said bell crank levers 26 bearing against a disc 29 secured to a hub member 30 splined to, but longitudinally 100 slidable on, shaft 1, and which hub member 30 on its upper end carries a similar disc 31. These discs on their facing sides are provided with spiral ribs 32, thus forming oppositely facing spirally faced disc gears. 105 Interposed between these discs so as to be engaged by either one thereof, one at a time, is a toothed gear 33 secured to a shaft 34 mounted in bearings 35 in the walls of the casing 6. This shaft is provided with a 110

worm gear 37 meshing with a worm wheel 36 on the shaft 38 mounted in bearings 39 in the casing 6 and lying at right angles to shaft 34. On shaft 38 is a disc 40 provided with an arm 41 on which the bell crank lever 21 is fulcrumed at 42. Disc 40 is provided with a pair of spaced peripheral stop projections 43 adapted to alternately engage with a fixed stop 44 projecting inward from the casing 6. The connection between shaft 38 and disc 40 is a yielding one, preferably of the friction clutch type, and as illustrated comprises a second disc 45 secured to the shaft 38, an interposed friction member 46 composed of material such as used for brake band linings, and a helical spring 47 surrounding shaft 38 and serving to hold the two discs 40 and 45 in frictional engagement. A collar 48 threaded to shaft 38 serves to vary the tension of spring 37 to adjust the degree of friction between discs 40 and 45.

The operation of the mechanism described is as follows:

Normally the gear 33 is out of mesh with both of the spirally faced gears 29 and 31. The shaft 1 is rotated from the motor and at a speed varying with the variation of the motor speed. When the speed of the motor increases beyond a predetermined speed, the centrifugal arms 10 overcome the resistance of spring 14 and thus pull downwardly on the links 12. This lowers the member 13 and this, through the lever 18, link 20, bell crank lever 21 and connecting rod 22, will quickly shift the power element control device. A slightly further downward movement of member 13 will permit the bell crank levers 26 to shift so as to allow the member 30 to drop by gravity (or spring) until the upper spirally faced gear 31 meshes with the gear 33, thus setting in rotation the shaft 34 which in turn rotates the disc 40 through the friction clutch mechanism described. This has the effect of shifting the fulcrum 42 of bell crank lever 21 and cumulatively but slowly further shifting the power element control device as will be obvious. Should this speed continue for a material length of time the disc 40 will be rotated to such an extent that one of the peripheral stops 43 thereon will contact with the fixed stop 44, whereupon the friction clutch will slip and there will be no further movement of the disc 40, and the fulcrum 42 will not be carried beyond a point where a reverse effect on the power element control device will be produced. When the motor speed drops, the spring 14 forces the member 13 upwardly, thus quickly adjusting the power element control device in reverse direction, through the lever 18, connecting link 20, bell crank lever 21, and connecting rod 22. If this lowered speed continues, the member 13 rises still farther and through its cone face 65 rocks bell crank levers 26 so as to lift the

member 30 until the lower spirally faced disc 29 is brought into engagement with the gear 33 on shaft 34, thus rotating disc 40 in the opposite direction, and slowly but cumulatively further shifting the power element control device in the opposite direction. This movement will continue until the gear 33 is disengaged from disc 29 or until the other one of the peripheral stops 43 on disc 40 contacts with the fixed stop 44, whereupon further shifting of the fulcrum 42 is prevented, the frictional clutch again slipping, as before described.

In some applications of the invention, as, for instance, for controlling automobile engines, a manual control is necessary in addition to the governor. Under these conditions the governor attempts to overcome the changes in engine speed due to adjusting the manual control, and hence the frictional clutch mechanism hereinbefore described is operating during all of such time. When, however, the engine is not subjected to a manual control, the governor merely has to take care of such variations as are due to changes of conditions, such as changes in load, changes in atmospheric conditions (in the case of internal combustion engines), and the like. Under these circumstances the speed is governed almost entirely by the quick acting mechanism, the member 30 generally floating so as to have neither of the gears 29 or 31 in mesh with gear 33.

The mechanism described is reliable in operation, and provides not only a rapid but also a very fine and accurate adjustment of the power element control device giving a quick initial adjustment thereto to quickly regulate the speed of the motor, and thereafter a finer adjustment to bring the motor to the desired speed. It will hold the motor at a substantially constant speed within very narrow limits.

I claim:

1. In a speed responsive device for operating the control element of a controllable machine, the combination of a rotating shaft driven from the motor, a lever element arranged to be quickly displaced by variations in the shaft speed, a rotatable member on which said lever member is fulcrumed, means independently operated by variation in the shaft speed to move said rotatable member, and means for limiting the extent of movement of said rotatable member in both directions.

2. In a speed responsive device for operating the control element of a controllable machine, the combination of a rotating shaft driven from the motor, a lever element arranged to be quickly displaced by variations in the shaft speed, a rotatable member on which said lever member is fulcrumed, means independently operated by variation in the shaft speed to shift said rotatable

member, and means for limiting the extent of movement of said rotatable member in both directions, the means for operating said rotatable means including a yielding or slip connection arranged to yield when said rotatable member reaches the limit of its movement in either direction.

3. In a speed responsive device for operating the control element of a controllable machine, the combination of a rotating shaft driven from the motor, a centrifugal governor thereon, a rotatable shiftable member connected to the control element of the controllable machine, connections from said governor whereby to quickly displace said control element, means independently operated by variation in the shaft speed to slowly displace said shiftable member, and means to limit the extent of movement of said shiftable member in both directions.

4. In a speed responsive device for operating the control element of a controllable machine, the combination of a rotating shaft driven from the motor, a centrifugal governor thereon, a rotatable member connected to the control element of the controllable machine, a connection from said governor whereby to quickly displace said control element, means independently operated by variation in the shaft speed to slowly displace said rotatable member, and means to limit the extent of movement of said rotatable member in both directions, the means for shifting said rotatable member including a yielding or slip connection arranged to yield when said rotatable member reaches the limit of its movement in either direction.

5. In a speed responsive device for operating the control element of a controllable machine, the combination of a rotating shaft driven from the motor, a centrifugal governor thereon, a lever element connected to the control element of the machine, a rotatable member on which said lever member is fulcrumed, means actuated by said governor for quickly displacing said lever element, and means independently operated by variation in the shaft speed to slowly actuate said rotatable member.

50 6. In a speed responsive device for operating the control element of a controllable machine, the combination of a rotating shaft driven from the motor, a centrifugal governor thereon, a lever element connected to the control element of the machine, a rotatable member to which said lever member is operatively connected, means actuated by said governor for quickly displacing said lever element, means independently operated by variation in the shaft speed to slowly rotate said rotatable member, and means to limit the extent of movement of the rotatable member in both directions.

65 7. In a speed responsive device for operating the control element of a controllable

machine, the combination of a rotating shaft driven from the motor, a centrifugal governor thereon, a lever element connected to the control element of the machine, a rotatable member to which said lever member is operatively connected, means actuated by said governor for quickly displacing said lever element, means independently operated by variation in the shaft speed to slowly rotate said rotatable member, and means to limit the extent of movement of the rotatable member in both directions, the means for rotating said rotatable member including a yielding or slip connection arranged to yield when said rotatable member reaches the limit of its movement in either direction.

8. In a speed responsive device for operating the control element of a controllable machine, the combination of a rotating shaft driven from the motor, a rotatable member operatively connected to the machine control element, reversely arranged gears on said shaft, an interposed gear arranged for connection to either one of said reversely arranged gears and operatively connected to said rotatable element, a centrifugal governor on said shaft, means actuated by said governor to bring either of said reversely arranged gears into operative connection with the interposed gear, and independent connections from said governor to the machine control element for quickly displacing the same.

9. In a speed responsive device for operating the control element of a controllable machine, the combination of a rotating shaft driven from the motor, a rotatable member operatively connected to the machine control element, reversely arranged gears slideable on said shaft, an interposed gear adapted to engage either one of said reversely arranged gears and operatively connected to said rotatable element to slowly rotate the same, a centrifugal governor on said shaft, means actuated by said governor to bring either of said reversely arranged gears into engagement with the interposed gear, and independent connections from the said governor to the machine control element to quickly move the same.

10. In a speed responsive device for operating the control element of a controllable machine, the combination of a rotating shaft driven from the motor, a shiftable member operatively connected to the machine control element, a pair of spaced disks slidably mounted on said shaft, an interposed element arranged to be actuated by either of said disks and operatively connected with said shiftable member, a centrifugal governor on said shaft, a cam sleeve on said shaft interposed between said governor and said disks, and independent connections from said governor to the said control element.

11. In a speed responsive device for operating the control element of a controllable machine, the combination of a rotating shaft driven from the motor, a shiftable member 5 operatively connected to the machine control element, a pair of spaced disks slidably mounted on said shaft, an interposed element arranged to be actuated by either of said disks and operatively connected with 10 said shiftable member, the operative connection including a friction clutch arranged to yield when said shiftable member reaches the limit of its movement in either direction, a centrifugal governor on said shaft, 15 a cam sleeve on said shaft interposed between said governor and said disks, and independent connections from said governor to the said control element.

12. In a speed responsive device for op-

erating the control element of a controllable 20 machine, the combination of a rotating shaft driven from the motor, a lever element arranged to be quickly displaced by variations in the shaft speed, a counter-shaft, an oscillating member on the counter-shaft on 25 which said lever is fulcrumed, means independently operated by variations in the shaft speed to rock the oscillating member, and means for limiting the extent of movement of said oscillating member in both di- 30 rections.

In testimony whereof, I have hereunto set my hand.

SAMUEL M. KINTNER.
